UNITED STATES PATENT OFFICE.

WILLIS G. FAWCETT, OF SALEM, OHIO.

DESIGN FOR AN UMBRELLA-RACK.

43,955.

Specification for Design.

Patented May 6, 1913.

Application filed February 14, 1913. Serial No. 748,462. Term of patent 14 years.

To all whom it may concern:

Be it known that I, WILLIS G. FAWCETT, a citizen of the United States, residing at Salem, in the county of Columbiana and State of Ohio, have invented a new, original, and ornamental Design for an Umbrella-Rack, of which the following is a specification, reference being had to the accompanying drawing, forming part thereof.

In the drawings Figure 1 is a perspective

view of an umbrella rack embodying my new design. Fig. 2 is a side elevation of the same.

I claim:

The ornamental design for an umbrella rack, substantially as shown.

WILLIS G. FAWCETT.

Witnesses:

F. B. HARRIS,

R. H. HAWKINS.
